REED SWITCH ENVELOPE

Bernard Edward Shlesinger, Jr., 3906 Bruce Lane,
Annandale, Va. 22003

Filed Sept. 17, 1969, Ser. No. 19,196

Term of patent 14 years

Int. Cl. D13—03
U.S. Cl. D26—13

Fig. 1

Fig. 2

Fig. 3

Fig. 4

Fig. 5

Fig. 6

Fig. 7

FIG. 1 is a front elevational view of the reed switch envelope showing my new design;

FIG. 2 is a right side elevational view thereof;

FIG. 3 is a top plan view thereof;

FIG. 4 is a bottom plan view thereof;

FIG. 5 is a front elevational view of a modified form of the reed switch envelope described in FIG. 1 showing my new design;

FIG. 6 is a top plan view thereof;

FIG. 7 is a bottom plan view thereof.

The sides opposite to the sides shown in FIGS. 1, 2, and 5 are identical to these respective figures.

I claim:

The ornamental design for a reed switch envelope, as shown and described.
